UNITED STATES PATENT OFFICE

MAZIE B. HOMER, OF BALTIMORE, MARYLAND

DISPENSING ATTACHMENT FOR COLLAPSIBLE TUBES

Application filed April 29, 1930. Serial No. 448,189.

My invention relates to an improved dispensing attachment for collapsible tubes such as are commonly employed as containers for pastes, creams, artists' paints and similar materials, which are ejected from the tube by compressing the latter.

One object of the invention is to provide an exceedingly cheap and simple device for the discharge-end of the tube whereby the same may be quickly opened or closed without the necessity of threading a cap thereon.

Another object is to provide an improved device for such tubes wherein a sliding valve 15 is employed to effectually cut off the material discharging from the tube and seal the latter against the atmosphere.

A further object is to provide an improved valve device for such tubes wherein the valve, 20 whether in its open or closed positions, will not project from the casing in which it is confined or expose a gummy or sticky surface that can come in contact with the hands of a user, and

25 A still further object is to provide an improved valve device for collapsible tubes which may readily be attached to the ordinary nozzle of such tubes in place of the screw cap which is so commonly employed there- 30 on.

With these, and other objects in view, the invention is shown in the accompanying drawing wherein,—

Fig. 1 shows a collapsible tube in front elevation with my improved valve-device thereon.

Fig. 2 illustrates the same in side elevation, as viewed from one side thereof.

Fig. 3 shows the same as viewed from the 40 opposite side thereof.

Fig. 4 illustrates a portion of the tube on an enlarged scale, with the improved device thereon, but shown in section, with the valve in the open position and the contents being 45 discharged therefrom onto a tooth brush, and

Fig. 5 shows a cross-sectional detail through the tubular valve-body.

Referring to the several parts of the device 50 by reference characters, the numeral 6 designates a collapsible tube, such as is common-

ly employed as a container for tooth paste, cream or other semi-fluid substances.

These tubes usually have a breast 7 and a nozzle 8 projecting therefrom.

If the device is to have the form of an 55 attachment for such tubes, so that it may be detached therefrom, then the nozzle 8 will be provided with means for effecting such attachment, such for example, as exterior screw-threads 9, as shown in Fig. 4.

60 While the improved device may be used to dispense a measured quantity of the material, I lay no stress on this point, as the user may operate the device to eject only a measured quantity of the substance or not as desired. 65 It is my observation that some users prefer more of the substances at a time than others and I have therefore designed the structure in order that the user may dispense such quantity as may be desired.

70 The improved device in this instance has the form of an attachment and consists of a short tubular body 10 having an interiorly 75 screw-threaded socket 11 at its inner end to screw over the nozzle 8, and at its outer end 12, said body is preferably beveled and has an eccentrically-located semi-circular port 13 in the higher portion of said beveled end.

On the interior of the body 10, and in alignment with the eccentric semi-circular end- 80 port 13, I provide a valve-chamber 14 which latter extends in a direction parallel with but to one side of the longitudinal central axis of the tube and its nozzle-passage.

85 This valve-chamber 14 is permanently closed at its inner end 15, and in cross-section, said chamber is semi-circular as clearly shown in Fig. 5, with one flat face 16.

The circular wall of the tubular body 10 90 is provided with a longitudinal slot 17 which opens into the valve-chamber 14, for a purpose that will presently be explained.

A longitudinal passage 18 is also provided on the interior of the tubular body 10. The 95 rear end of this passage extends around the inner closed end 15 of the valve-chamber 14, while the outer end of this passage extends laterally across the front end of the valve-chamber and communicates with the semi- 100

circular port 13, in the outer end 12 of the body.

This passage 18 is therefore the dispensing passage, in that its inner end communicates with the nozzle of the collapsible-tube, while it extends around the valve-chamber and opens at the discharge-port 13.

A slide valve 19 is positioned in the valve-chamber and is semi-circular in cross-section 10 to conform to the cross-sectional shape of that chamber. The forward end 20 of this valve is beveled to correspond to the beveled end 12 of the tubular body so that when the valve is moved forward to the ejecting and 15 sealing position, the forward end will be flush with the beveled forward end of the body, as shown in broken lines in Fig. 1.

Another advantage in beveling the forward end 20 of the valve is, that when it is moved 20 forward against the charge of paste in front of it, its beveled edge will cut its way and shear the paste from the surrounding walls and thus clean the walls at each forward stroke, thereby preventing the paste from 25 leaking around the valve and working rearwardly into the valve-chamber.

A headed pin 21 passes through the longitudinal slot in the tubular body and enters the slide valve 19 whereby the latter may 30 readily be actuated by the fingers of the user to move the valve to either a closed or open position.

The operation of the device, it is believed, can readily be understood by reference to Fig. 35 4, wherein the valve is shown retracted to open the dispensing passage. When the valve is in this retracted position, slight pressure on the tube will force the contents through the said passage and out through the port 40 13. If a tooth-brush 22 is held in front of the beveled end 12 of the tubular body, the paste may be distributed thereover.

Having described my invention, I claim,—

1. A collapsible tube, a tubular body at one 45 end of the collapsible tube and communicating with the interior thereof said tubular body having an interior valve-chamber and also having an interior dispensing passage which extends along one side of the valve-chamber with its forward end extending laterally in front of the valve-chamber said body also having a discharge-port eccentrically-located with respect to its longitudinal axis and a slide-valve in said valve-chamber 55 said slide-valve having both of its ends on the interior of the tubular body when the valve is in the open position.

2. A collapsible tube, a tubular body at one end of said collapsible tube said tubular body having an outer end with an eccentrically-located discharge-port therein said body also having a valve-chamber on the interior thereof which is also eccentrically-located with respect to the longitudinal axis of 60 the body and in alinement with said port

and said body also having a dispensing passage which extends along one side of the valve-chamber and terminates at a point in front of said chamber, a slide-valve arranged in the valve-chamber with both of its ends concealed on the interior of the body when it is in the retracted open position and means extending laterally from the slide-valve to the exterior of the body for operating said valve. 70

3. A collapsible tube, a tubular body extending axially from the end of the said tube, said body having an eccentrically-located port in its end and a longitudinal slot in one side between its opposite ends,—said tubular body also having a valve-chamber in alinement with the eccentrically-located end port which chamber is entirely closed at its inner end, the body also having a dispensing passage whose inner end communicates with the collapsible tube beyond the closed end of the valve-chamber and whose outer end terminates in front of the valve-chamber, a slide-valve in the valve-chamber with both ends concealed therein when said valve is in the open position and means extending through the longitudinal slot of the tubular body and engaging the valve for operating the same. 80

In testimony whereof I affix my signature. 85
